F. J. W. BARROW.
DOOR HINGE.
APPLICATION FILED MAY 14, 1921.

1,400,788.

Patented Dec. 20, 1921.

UNITED STATES PATENT OFFICE.

FREDERICK J. W. BARROW, OF CHICAGO, ILLINOIS.

DOOR-HINGE.

1,400,788.

Specification of Letters Patent.

Patented Dec. 20, 1921.

Application filed May 14, 1921. Serial No. 469,429.

To all whom it may concern:

Be it known that FREDERICK J. W. BARROW, a citizen of the United States, residing at Chicago, in the county of Cook and State 5 of Illinois, have invented new and useful Improvements in Door-Hinges, of which the following is a specification.

This invention relates to doors and the hinge mounting thereof, and its object is to 10 provide a structure that will leave no space between the hinge edge of the door and the door casing, and hence eliminate all danger of persons getting their hands caught and injured.

15 The object stated is attained by means of a novel combination and arrangement of parts to be hereinafter described and claimed, and in order that the same may be better understood, reference is had to the accompanying drawing forming a part of this specification.

In the drawing,

Figure 1 is an elevation of the door; Fig. 2 is an enlarged section on the line 2—2 of 25 Fig. 1; Fig. 3 is a view similar to Fig. 2 showing the door partly open; Fig. 4 is an enlarged section on the line 4—4 of Fig. 1; Fig. 5 is a vertical section on the line 5—5 of Fig. 1; Fig. 6 is a view similar to Fig. 4 30 showing a modification, and Figs. 7 and 8 are sectional details showing further modifications.

Referring specifically to the drawing, 10 denotes a door and 11 one of the sides of the 35 frame to which the door is hinged. Fig. 1 shows the door fitted with two hinges, and as they are alike, a description of one suffices for both.

The hinge member which is secured to the 40 door 10 is composed of a base or attaching plate 12 and cylindrical knuckles 13 integral therewith, and the hinge member which is secured to the casing 11 is composed of a base plate 14 and integral cylindrical knuckles 15. Each hinge member has two knuckles which are spaced so that when the members are assembled the knuckles are all in 45 axial alinement. It will be understood of course that the hinge members may be provided with any number of knuckles. The 50 pintle of the hinge is a hollow cylinder 16 which seats in the knuckles 13 and 15, and provides the pivotal connection between the two hinge members as usual.

55 The base plate 12 of the hinge member which is to be attached to the door is ar-

ranged tangentially with respect to the knuckles 13 that it can be attached to the edge of the door 10, and the base plate 14 of the other hinge member is arranged in a 60 similar manner for attachment to the edge of the casing 11. The two hinge members are duplicates, and their base plates have perforations through which pass the screws or other fasteners 17 whereby they are secured in place on the door and its casing, 65 respectively.

The diameter of the knuckles 13 is just double the thickness of the door 10 which leaves one half of the knuckles projecting 70 beyond the plane of the face of the door, and locates the other half between the edge of the door and the edge of the door casing 11 to which is attached the hinge member composed of the parts 14 and 15, and this last-mentioned hinge member occupies a 75 corresponding relation with respect to the door casing.

In order to close up on one side of the door those portions of the space not occupied by the hinges, there is attached to the casing 11 a molding strip 18, and on the opposite side the space is closed up by a molding strip 19 carried by the door 10, the latter strip being secured to project from the 80 hinge edge of the door. The strip 18 is three quarters round in cross section, and it is fitted over the corner of the casing as shown in Fig. 4. Where the hinge member of the casing is attached, the casing is recessed to a depth to locate the knuckles 15 85 in alinement with the knuckles 13, the width of the space between the door edge and the recessed casing edge at the hinges corresponding to the external diameter of the 90 knuckles 13 and 14. The strip 18 is therefore in axial alinement with the hinge knuckles and it completely closes up on one side of the door the gap between the hinge edge thereof and the opposite edge of the door 95 casing. The strip 19 for closing up this gap on the other side of the door, is secured to the face of the door and it projects beyond the hinge edge thereof close up to the casing edge to tangentially fit the 100 molding 18 at this side. The strip 19 is also continued across the hinges to cover the gap between the base plates 12 and the knuckles 13. The strip 18 however is not continuous but is made in three sections, one 105 section seating between the hinges, and the other sections above and below the hinges

110

as shown in Fig. 1, and adjoining the hinges, the ends of the sections are reduced to form tenons 20 which seat in the hollow pintles 16, and thereby assist to hold in hinge members in assembled relation.

Fig. 6 shows a molding strip 21 for the same purpose as the strip 18, but shaped somewhat differently. This strip is to be used where the hinge recesses of the casing are continuous from the top to the bottom of the casing, said strip 21 being shaped to fill up the recess beyond the site of the hinges.

Figs. 7 and 8 show molding strips 22 and 23, respectively corresponding to the molding strip 19 but somewhat different in shape, they being substantially triangular to fit into the space between the plate 12 and the knuckles 13.

It will be evident from the foregoing that the crack between the door and its casing is completely covered at all times and irrespective of the position of the door, and hence all danger of persons getting their hands caught and injured between the casing and the door edge is eliminated.

As shown in Fig. 1, the base plates 12 and 14 of the hinge members project from the ends of the knuckles a sufficient distance to permit ready application of the fasteners 17, the holes for the latter being in the projecting ends of the base plates.

I claim:

1. The combination with a door and the casing to which it is hinged, of a hinge consisting of similar members each of which is composed of an attaching plate and knuckles, the knuckles of the two members registering, and a pintle passing through the registering knuckles, strips carried by the casing for closing up on one side of the door the gap between the casing edge and the opposite edge of the door beyond the hinges, said strips being in alinement with the hinge

knuckles and coinciding in cross-section to the cross-sectional contour thereof, and a strip for closing up said gap on the other side of the door, said last-mentioned strip being carried by the door and also extending across the hinges to cover the gap between the door and the knuckles of the hinge member carried by the door.

2. The combination with a door and the casing to which it is hinged, of a hinge consisting of similar members each of which is composed of an attaching plate and knuckles, the knuckles of the two members registering, and a pintle passing through the registering knuckles, said pintle being hollow, strips carried by the casing for closing up on one side of the door the gap between the casing edge and the opposite edge of the door beyond the hinges, said strips being in alinement with the hinge knuckles and coinciding in cross-section to the cross-sectional contour thereof, the ends of the strips having tenons which seat in the aforesaid pintles, and a strip for closing up said gap on the other side of the door, said last-mentioned strip being carried by the door and also extending across the hinges to cover the gap between the door and the knuckles of the hinge member carried by the door.

3. A hinge comprising a pair of attaching plates having matching knuckles adapted to receive a pintle, said knuckles being offset laterally with respect to the plates, each of said plates extending tangentially with respect to its knuckles and having a length from the front to the rear which is less than the diameter of the knuckles, to locate the knuckles partly opposite the face of the plate and partly projecting beyond the plate.

In testimony whereof I affix my signature.

FREDERICK J. W. BARROW.
